poration of New Jersey

Application November 8, 1937, Serial No. 173,284
In Great Britain December 9, 1936

3 Claims. (Cl. 12—125)

This invention relates to the manufacture of shoes and is illustrated herein with reference to a method of and a clamping device for applying heel-breast covering flaps to shoes.

5 In the manufacture of shoes having Louis heels it is common practice to cover the breast of the attached heel of the shoe by a flap which is split from the grain side of the heel end of the sole of the shoe. In order that heel-breast receiving shoulders may be conveniently formed upon the attached sole of the shoe and in order to enable the operator to form a smooth joint between the lip of the heel and the shank portion of the sole of the shoe it is common practice to split the flap a considerable distance forward of the heel-breast line of the sole. The flap is later secured to the shank portion of the sole of the shoe and to the breast of the heel through the use of a suitable adhesive.

10 A device for effectively clamping breast flaps in place against shoes while the adhesive which is commonly applied to the flap and to the heel dries, is disclosed in British Letters Patent No. 202,574. Such a device operates satisfactorily on shoes in which the flap-forming split in the sole extends only a short distance forward of the heel-breast line of the shoe. Said device, however, does not operate effectively on different sizes and shapes of shoes the flaps of which are split considerable distances forward of the heel-breast lines of the shoes, without selectively substituting rubber pads of different sizes and shapes for the rubber pad of the device which forces the flap against the shank portion of the sole and the breast of the heel.

15 It is an object of this invention to provide an improved clamping device of the general type disclosed in British Letters Patent No. 202,574 by the use of which heel-breast covering flaps extending considerable distances forward of the heel-breast lines of shoes of various sizes and shapes can be clamped effectively against the shank portions of the soles and against the breasts of the heels of the shoes without having to change the pads of the device.

With the above object in view, and in accordance with a feature of this invention, there is provided a clamping device comprising a support for a shoe, a saddle conformable to the shank portion of the sole of the shoe and to the projecting portion of the breast of a heel attached to the shoe, means for causing the saddle to force a covering flap split from the sole of the shoe against the shank portion of the sole and the projecting portion of the breast of the heel,

a resilient pad, and means for causing said pad to force the saddle with considerable pressure against the portion of the flap overlying the shank portion of the sole and the projecting portion of the breast of the heel and also to force the flap with considerable pressure against the lower portion of the breast of the heel.

As will appear from the detailed description which follows, the saddle serves to distribute over the portion of the sole near the forward end of the split the pressure which is applied through it and obviates the frequent substitution of pads of different shapes and sizes.

The various features and advantages of the invention will be understood and appreciated from the following detailed description read in connection with the accompanying drawing, in which

Fig. 1 shows in side elevation the illustrated device and a shoe clamped in said device;

Fig. 2 is a view on line II—II of Fig. 1; 20

Fig. 3 is an illustrative view showing the heel-breast covering flap clamped against the shoe in the clamping device; and

Fig. 4 is an enlarged view showing portions of the mechanism for operating the saddle. 25

A plurality of the illustrated clamping devices, which are similar in many respects to the clamping devices disclosed in said British Letters Patent No. 202,574, may be advantageously mounted upon a turret (not shown) of the machine disclosed in British Letters Patent No. 343,151. The base 20 of the illustrated clamping device comprises a pedestal 22 provided with a pin 24 (Fig. 1) shaped to fit in a recess 26 formed in the cone of a last 28 upon which is mounted a shoe 30. As above stated, it is common practice to split from the grain side of the heel end of the sole 32 of the shoe a heel-breast covering flap 34 (Fig. 3) extending a considerable distance forward of the heel-breastline 36 of the sole. After 40 the lip 38 of the heel and the rear end of the shank portion of the sole of the shoe have been properly jointed the flap 34 is secured to the shank portion of the sole and to the breast of the heel through the use of a suitable adhesive. 45

Pivoted upon the opposite ends of a rod 43 (Figs. 1 and 2) secured to the base 20 of the clamping device are a pair of depending arms 42 riveted to offset levers 44 having recesses for receiving studs 46 (Figs. 1 and 3) secured to a header 48 (Fig. 3). Mounted upon the studs 46 and positioned outside the respective levers 44 are a pair of plates 50 riveted to the lower ends of a leather saddle 52 which is about two inches wide and approximately one-eighth of an 55

inch thick. The upper portion of the saddle 52 is molded to approximately the shape of the portion of the shoe with which it is to engage, and the forward portion 54 (Fig. 3) of the saddle is 5 beveled so that its outer face merges with the covered breast of the heel.

Interposed between the ends of the header 48 and the levers 44 are spring washers 56 (Fig. 4) which cause friction between the plates 50 on 10 the one hand and the levers 44 and the heads of the studs 46 on the other hand, thereby preventing the plates 50 and the lower ends of the saddle from moving freely about the studs 46. The levers 44 are normally urged in a counter-clockwise direction (Fig. 1) by springs 58, the rear 15 ends of which are secured to a bracket 60 screwed to the base 20 of the machine and the forward ends of which are secured to the lower ends of the depending arms 42. Movement of 20 the arms 42 in a clockwise direction is limited by the engagement of the header 48 (Fig. 4) with the face 62 (Fig. 1) of the base 20.

In the operation of the machine disclosed in said British Letters Patent No. 343,151 equipped 25 with a plurality of clamping devices such as illustrated herein, the operator takes from a steam stand (not shown) of the machine a shoe which has been allowed to remain upon the stand long enough to cause the adhesive on the flesh side of 30 the flap and the breast of the heel to become tacky and the material of the flap to become softened, and places the last 28 upon which the shoe is mounted, upon the pin 24. The operator then lays the breast flap 34 against the shank 35 portion of the sole of the shoe and the breast of the heel and smooths the flap upon the breast by the use of a rub-stick, after which the saddle 52 is placed upon the shoe in the position illustrated in Fig. 1. In placing the saddle 52 on the 40 shoe, the operator preferably grasps the opposite sides of the saddle, raises the saddle until its upper end can be moved over the heel, and then allows the spring 58 to draw the saddle down against the shoe. The saddle 52 tends to hold 45 the heel portion of the cone of the last 28 against the pedestal 22 thereby preventing the forepart of the shoe from tipping forward. After placing the saddle on the shoe the operator usually pounds against the saddle with a hammer thereby 50 causing the flap to be forced with considerable pressure against the shank portion of the sole of the shoe and the projecting portion of the breast of the heel. The pressure of the saddle 52 against the shoe tends to retain the effects of the 55 above-mentioned pounding operation. The saddle 52, which adopts itself to the lateral curvatures of the different lasts and thus assists in conforming the sole and the applied flap to the last, protects the breast flap from being marred 60 during the pounding operation.

After positioning the saddle 52 over the shank portion of the sole and the forwardly projecting portion of the breast of the heel and pounding against the saddle as above described, a pair of 65 rubber pads 64, 66 similar to the pads disclosed in said British Letters Patent No. 202,574, are positioned adjacent to the rear and breast faces respectively of the heel and are then forced with considerable pressure against said faces. 70 The pad 64 is carried by a holder 68 pivoted to the upper ends of a pair of links 70, and the pad 66 is carried by a holder 72 pivoted to the upper ends of another pair of links 74. Right and left pairs of links 70, 74 are pivoted together 75 at their central portions, the lower portions of

said links being pivoted to links 76 connected to a hand lever 78. The hand lever 78 is hinged at its rear ends upon the rods 40 and carries a pair of pawls 80 which may be forced into engagement with the ratchet teeth 82 formed upon a forward extension of the base 20 and which are normally held away from the ratchet teeth by leaf springs 84.

The pads 64, 66 are moved downward and toward each other to force the same against the 10 breast and rear faces of the heel by depressing the hand levers 78, which may be locked in its lowered position, by swinging the pawls 80 into engagement with the ratchet teeth 82. As the pad 64 is moved downward it forces the saddle 15 52 against the shank portion of the sole of the shoe and the forwardly projecting portion of the breast of the heel and also forces the flap 34 against the lower portion of the heel breast. The operator ceases to depress the hand lever 78 20 when the pads 64, 66 have been forced with sufficient pressure against the shoe.

After the operator has clamped the shoe in one of the illustrated clamping devices incorporated in the machine disclosed in said British Letters 25 Patent No. 343,151 he trips a clutch of the machine thereby causing said clamping device to be moved away from a loading station and causing another clamping device which carries a shoe and has passed around the machine to be moved to said 30 loading station. The operator then proceeds to remove the shoe from the clamping device which has been swung around to its loading position, by depressing the hand lever 78 and causing the pawls to be moved by the springs 84 away from 35 the ratchet teeth 82, and then raising the hand lever and the pads 64, 66 so that the latter may be swung forward and downward into an inoperative position. The saddle 52 is then removed from the shoe by grasping it at each side of the 40 shoe and raising it so that it may be moved forward away from the shoe, the saddle when being lowered by the action of the springs 58. Downward movement of the header 48 (Fig. 4), as has been explained above, is limited by engagement 45 with the face 62 (Fig. 1) of the base of the machine. If desirable the shoe 30 and the saddle 52 may be raised together, the forepart of the shoe being raised with a vertical turning movement so that the heel passes out of the saddle 50 when the shoe has been raised above the top of the last pin 24. The operator then takes another shoe from the steam stand and places it in the clamping device.

The illustrated clamping device may be advantageously used in operating upon a shoe the breast flap of which extends just forward of the heel-breast line of the shoe, since the saddle 52 affords protection for the shoe during the pounding operation in addition to other benefits such, 60 for example, as distributing the pressure of the pad 64 over the portion of the breast flap which covers the shank portion of the sole of the shoe and the projecting portion of the breast of the heel.

Having described the invention, what we claim as new and desire to secure by Letters Patent of the United States is:

1. In a clamping device, a support for a shoe, a saddle conformable to the shank portion of the 70 sole of the shoe and to the projecting portion of the breast of a heel attached to the shoe, means for causing said saddle to force a covering flap split from the sole of the shoe against said shank portion of the sole and said projecting 75

portion of the breast of the heel, a resilient pad, and means for causing said pad to force the saddle with considerable pressure against the portion of the flap overlying the shank portion 5 of the sole and the projecting portion of the breast of the heel and also to force the flap against the lower portion of the breast of the heel.

2. In a clamping device, a support for a shoe, 10 a saddle conformable to the shank portion of the sole of the shoe and to the projecting portion of the breast of a heel attached to the shoe, yieldable means for causing said saddle to force a covering flap split from the sole of the shoe 15 against said shank portion of the sole and said projecting portion of the breast of the heel, said saddle having a margin which is beveled to cause the outer face of the saddle to merge with the covered breast of the heel, a resilient pad, and 20 means for causing said pad to force the saddle with considerable pressure against said portion of the flap overlying the shank portion of the sole and the projecting portion of the breast of the heel and also to force the portion of the 25 flap not engaged by the saddle against the lower portion of the breast of the heel.

3. In a clamping device, a support for a shoe

comprising a heel and a sole which has been split to provide a heel-breast covering flap, a saddle conformable to the shank portion of the sole of the shoe and to the projecting portion of the breast of a heel attached to the shoe, yieldable 5 means for urging the saddle rearward and toward the shoe upper to cause the saddle to force the flap against the shank portion of the sole of the shoe and against the projecting portion of the breast of the heel, a resilient pad, means 10 for forcing said pad with considerable pressure against the saddle and against the portion of the flap in engagement with the lower part of the breast of the heel, said pad being movable toward and away from the shoe independently of 15 the saddle to enable the operator to pound against the saddle in order to conform the flap to the projecting portion of the breast of the heel and to conform the shank portion of the sole and the portion of the flap applied thereto 20 to the shape of a last upon which the shoe is mounted, and means for maintaining the pad in clamped relation with the shoe until adhesive used in securing the flap to the shoe dries.

THOMAS BAGGOTT CLARKE.
